INVENTOR
Harry E. Radack
BY *R. L. Miller*
ATTORNEY

UNITED STATES PATENT OFFICE

HARRY E. RADACK, OF NEW YORK, N. Y.

CONVENIENCE OUTLET

Application filed May 14, 1931. Serial No. 537,383.

This invention relates to new and useful electrical outlets, commonly known as convenience outlets in general, and particularly to an electrical device adapted to receive the 5 prongs or blades of what is known as an electric plug or connector.

The object of my invention is to provide a simple and comparatively inexpensive article of this kind which has the marked advantages of consisting of two distinct members adapted to be normally in spring or snap contact with each other, thereby not only facilitating the attachment of the article to any desired object, but also enabling a 15 quick and unrestricted connection with the device of electric conductors leading thereto and therefrom.

Another object of my invention is to provide in connection with my device means for guiding and restricting the movement of the spring contact members of the article when in use, i. e., when the movement of the spring contact members is caused by the insertion of the prongs or blades of a connector.

Another object of my invention is to provide an article of this kind consisting of what may be termed as a base member and a cover member so arranged as to enable the unrestricted attachment of the base member 30 when the cover member is removed, or to provide the permanent association of the two members together in the event the base member is not intended to be attached to an object.

The foregoing and further objects will be more fully apparent from the following description and the accompanying drawing forming part of my disclosure, but by no means intended to limit same to the actual showing, and in which

Figure 1 is a top view of the base member of my device.

Figure 2 is a side elevation of the base member and a cross sectional view of the cover member.

Figure 3 is a front elevation of my device, showing the base member in elevation while the cover member is shown in cross sectional view.

Figure 4 is a top view of the cover member.

Figure 5 is an enlarged detail view in cross section of a preferred form of a part of my device.

Figures 6, 7, and 8 represent illustrations of various types of spring contact members 55 employed in my device.

Figure 9 is a cross sectional view through my device including the base and the cover members and

Figure 10 is a bottom view of my cover 60 member in its preferred form.

Referring to the figures, numeral 10 denotes the bottom rim of my base member from which projects upwards a substantially annular extension 11 which is flattened on two sides as indicated at 12 while at right angles to the flattened sides there are provided wire receiving projections 13 equipped with grooves or depressions 14 for accommodating wire or cable leading into my device.

Projecting from the extension 11, there will be seen a center portion 15 provided with a central opening 16. Adjacent to and forming a continuation of the flattened portions 12, there will be seen spring contact supports 17 to which are attached by means of binding screws 18 spring contact members 19.

These contact members are plainly illustrated in Figures 5, 6, 7, and 8, and they consist of flat metal strips so shaped that their substantial middle portion rests upon seats 17, while their upper portions 19' extend beyond the seat and are turned upon themselves so as to form substantial V-shapes. 85 Their lower ends 19'' extend downwardly and are curved in a special form so as to comprise snap means, the function of which will be explained presently.

In Figures 1, 2, and 4, it will be seen that 90 seat portions 17 are provided with retaining ribs 17' intended for preventing the shifting of spring members 19 in their seats.

Adapted to practically completely cover the entire base member and particularly the 95 spring contacts, there is provided a cover member indicated at 20, and clearly shown in both cross section views in Figures 2, 3, and 9, and in top and bottom views of Figures 4 and 10.

The cover member comprises substantially a hollow annular shell which is provided with two slots indicated at 21, and clearly seen in Figure 10, which slots are adapted to engage cable rests 13, whereby the cover member is prevented from leaving its predetermined position. At right angles to slots 21, there are provided flattened enlargements 22 which are provided with internal and peripheral recesses 23 which are especially arranged for interlocking with snap arrangements 19" extending from seat portions 17 of the base member.

The inner portion of the cover member 20 is practically hollow except for a central ridge shown clearly in Figure 10 at 24. In that ridge, there are provided spring contact recesses 25 which are equipped with inclined ridges or walls 26, which are adapted together with the rest of the recess arrangements to not only guide the spring contact members, but also limit their movements when the prongs or blades of an electric connector is brought to bear against the contacts.

Forming a continuation of recesses 25 are two blade receiving holes 27 provided in the cover member, and their outer approach is beveled, as clearly shown in Figure 4 at 28.

In the solid center portion 24 of the cover member there is provided a central recess 29 which may be either threaded or plain and which serves for receiving an attaching screw adapted to pass through hole 16 of the base member, and permanently connect the base member to the cover member when the former is not intended to be attached to an object.

Ordinarily, the two members are in snap engagement with each other, and the base member is usually attached to the wall or any other object by passing through hole 16 a wood screw whereby the base member is secured.

The arrangement of connecting the base member together with the cover member by means of a screw 30 is clearly shown in Figure 9. In this case, the base member rests upon an object without being itself attached thereto.

In Figures 1, 2, 3, and 6, I have shown contact members made of a continuous strip of resilient material with the upper end portion bent upon itself towards the center of the base member. Also, the snap arrangement 19" is shown to be made of one piece with the spring contact member. In Figure 7, however, there will be seen that the bent-over top portion of the spring member is turned outwards while in Figure 8, the contact member consists of a portion marked 31 which is riveted together at 32 to a snap portion 33.

From the foregoing, it is evident that various arrangements may be made in developing the contact and snap members depending

upon the advantages derived from their respective arrangements. Thus, for instance, an arrangement shown in Figure 7 will allow the construction of my device to become smaller in diameter, as compared with spring contact arrangements shown in Figure 6.

Similarly, the attachment of the spring contacts to the base member may be altered so as to reduce the cost of manufacture and minimize the labor and material required.

In Figure 5, I have illustrated a binding screw 34 which engages a metal insert 35 imbedded in the material of the base member 10. Nevertheless, it is quite proper and effective to use binding screws directly in the material of the base member, as is shown, for instance, in Figure 2.

While I have found it expedient to use for the snap arrangement between the two members the extension of the spring contact, be it understood that any other arrangements may be provided to fulfill the function of providing a snap contact between the base and the cover members.

From the foregoing, it becomes evident that a great many modifications and changes may be made in my device without departing from the broad scope of my invention, and I, therefore, reserve for myself, the right to make such changes or alterations in my invention for which I claim:

1. In a convenience outlet, the combination with an attachable base member, of a removable cover member associated therewith, said base member provided with supporting means for spring contact members and means for providing a snap engagement with said cover member, an aperture provided in said base member accommodating an attaching screw or the like, a pair of spring contact members associated with said supporting means of the base member and attached to the former, said cover member comprising a substantially closed cap having two apertures for accommodating prongs of an electric plug or connector adapted to engage said spring contact members, a central recess provided in the body of said cover member for accommodating a screw for holding the base member permanently together with the cover member, when the latter is not attached to any object, a pair of recesses provided symmetrically within the cover member for accommodating and permitting, yet limiting the movement of said contact members, and means for accommodating and engaging said snap engagement means of said base member.

2. In a convenience outlet, a base member, a pair of spring contacts symmetrically arranged and attached to said base member, an aperture centrally provided in said base member, a pair of spring snap members associated with said base member, a cover mem-

ber adapted to register with and engage said base member and substantially cover the latter, a pair of recesses provided in said cover member, corresponding with and adapted to engage and further adapted to be engaged by said spring snap members, a central recess provided in the body of said cover member and aligned with the central aperture provided in said base member, the latter aperture serving for receiving either attaching means, whereby the base member may be secured to an object, or for means adapted to engage said cover member, when said base member is not to be attached to an object, a pair of elongated apertures provided at the upper face of said cover member and adapted to register with said spring contacts of the base member and further adapted to receive prongs of an electric connector or plug, a pair of recesses provided within the body of said cover member for accommodating said spring contacts, said recesses having inclined ridges for guiding and limiting the movement of said spring contacts.

25 In testimony whereof I affix my signature.
HARRY E. RADACK.
